[57] CLAIM

The ornamental design for a floor scraper attachment for a shoe, as shown and described.

DESCRIPTION

FIG. 1 is a front, top and side perspective view of the floor scraper attachment for a shoe showing my new design; FIG. 2 is a front elevational view thereof; FIG. 3 is a rear elevational view thereof; FIG. 4 is a side elevational view thereof, the side opposite being a mirror image of the side shown in FIG. 4. FIG. 5 is a top plan view thereof; and, FIG. 6 is a bottom plan view thereof.
